boro, N.C.Filed Feb. 4, 1963, Ser. No. 255,887
6 Claims. (Cl. 242—66)

The present invention relates to peripherally driven take-up rolls for knitting machines, especially circular knitting machines. The principal objects are to provide means for turning a take-up roll and to increase the tightness and compactness of the fabric on the roll, particularly in the later stages of a knitting run, and thereby to increase the continuous length of fabric which can be knit without interruption.

Circular knitting machines produce a tubular fabric which commonly is drawn upwardly from the needle cylinder or down through the cylinder, pressed flat and wound on a take-up roll. Generally, the rolls are equipped to handle relatively short continuous lengths of fabric, and, when this length has been knit, it is necessary to interrupt the knitting operation. For example, for fabrics knit from twisted paper yarn, the longest continuous length which can be made is about 100 yards. For many purposes, it is essential to have fabrics of greater length, such as 200—300 yards or more.

In a sense, larger take-up rolls are possible and it might seem that increasing the size of the rolls might be all that is required. However, there are basic limitations on the take-up mechanisms now in use which renders them unsuitable for long lengths of fabrics, even if they are increased in size.

A take-up mechanism of particular interest includes a large take-up roll on which the flattened tube of fabric is wound and a pair of squeeze or draw rolls, one above the other, which flatten the fabric as it passes between them. The upper draw roll peripherally engages the take-up roll and turns it. That is, the take-up roll itself is not driven directly but indirectly by the upper draw roll. The lower draw roll also may be driven by peripheral engagement with the upper draw roll. It will be appreciated that this arrangement assures that linear speeds of the peripheries of the rolls are the same.

The shaft of the take-up roll is mounted in vertical guides which permit it to move upwardly and downwardly. This provides for raising the shaft of the take-up roll to increase the distance between it and the upper draw roll to accommodate the fabric. As the amount of fabric increases, the angle of contact between the upper draw roll and the fabric on the take-up roll changes, and this is believed to reduce the ability of the draw roll to drive the take-up roll. Of course, this takes place as the driving force required increases because of the growing weight of fabric on the roll.

In addition, the fabric wound on the take-up roll in the later stages of a knitting run tends to be wound more loosely. This is believed to be caused by the necessity of the draw roll to support the weight of the take-up roll. As the weight of the fabric on the take-up roll increases, the draw roll must push harder to turn it and this forward pushing is applied to the take-up roll just as the fabric is being laid on, which is believed to loosen the fabric on the roll. Consequently, the tightness of

2

the fabric decreases from the inside of the roll to the outside and is non-uniform.

The present invention provides an improvement which avoids these difficulties. Briefly stated, an additional driving roller is provided near the fabric take-up roll which supplies additional peripheral driving power to the roll only after a substantial length of fabric has already been wound. The auxiliary drive roll engages the take-up roll shortly in advance of the upper draw roll. Preferably, the auxiliary roll also is turned slightly faster than the upper draw roll and has a smoother surface.

The invention will be illustrated by the following detailed description of a preferred embodiment, using a spring needle knitting machine and with reference to the drawing in which:

FIGURE 1 is an elevation of the upper part of a spring needle type knitting machine incorporating the present invention;

FIGURE 2 is a section along line 2—2 of FIGURE 1;

FIGURE 3 is a section along line 3—3 of FIGURE 1.

The spring needle knitting machine shown in the drawings is of the general type described in U.S. Patent 2,329,618 of W. A. Ingalls and the copending application of Robert Grey Egerton and James N. Lancaster for a knitting machine filed on January 7, 1963. Accordingly, only the take-up mechanism will be described in detail.

The take-up mechanism includes a take-up roll 1, upper draw roll 2, lower draw roll 3, and auxiliary drive roll 4. The four rolls are mounted for rotation within an inverted U-shaped carriage 5 above the needle cylinder and which turns in synchronism with the needle cylinder. There is a horizontal circular track 6 supported by upright posts of the frame 7 of the machine and the lower ends of the carriage for wheels which ride in the track. As the machine operates, the carriage turns on the track.

Above the carriage are two horizontal arms 8 and 8' of the frame which extend toward the center of the machine from upright posts and a horizontal plate 9 is suspended between them. There is a vertical opening 10 through the plate above the center of the carriage and a shaft 11 is journaled in it and welded to the top of the carriage. Near its top, above the plate 9, the shaft carries a bevelled gear 12. There is a D.C. motor 13 on top of the frame 7 near the shaft which drives it through a drive shaft 14 and a bevelled gear 15 which meshes with gear 12. The D.C. motor is synchronized by suitable conventional means with the needle cylinder drive.

The sides of the carriage are provided with suitably positioned bearings for the shafts of the rolls 1, 2, 3 and 4. The rolls 1, 2 and 3 are substantially in line, one above the other, rolls 2 and 3 being in fixed position. The bearings for the take-up roll 3 are slidably movable in vertical directions and vertical guides are suitably provided in the carriage for this purpose.

The auxiliary drive roll 4 is positioned outwardly from the draw rolls and slightly above the upper draw roll. In this position, it does not engage the fabric on the take-up roll initially. Thus, during the early stages of a knitting run, only an upper draw roll is in contact with the take-up roll but, as the run continues, the diameter of the take-up roll, including the fabric wound on, increases. Then, when the auxiliary roll first comes in contact with the take-up roll, the contact pressure is relatively light, but it increases as more fabric is wound on

the take-up roll. As will be explained further herein, the auxiliary roll tightens up the fabric on the take-up roll. The need for this tightening increases as the run progresses and more and more fabric is on the roll, so that the increasing pressure between the take-up roll and the auxiliary roll provides increased tightening effect as it is needed.

The exact positioning of the auxiliary roll will vary with the kind of fabric and the length of fabric to be knit in a run but the positions of the roll are given approximately by the equations

$$(1) \quad a = [b^2 + c^2 - 2bc \cos A]^{1/2}$$

in which:

a = distance between axes of take-up roll and auxiliary roll

b = distance between axes of take-up roll and upper draw roll

c = distance between axes of auxiliary roll and upper draw roll

A = angle between a line connecting the take-up roll axis with the upper draw roll axis and a line connecting the auxiliary roll axis with the upper draw roll axis.

$$(2) \quad b = t_1 + t_2$$

in which:

t_1 = radial thickness ($1/2$ of overall thickness) of upper draw roll

t_2 = radial thickness of take-up roll (including core and fabric).

The condition for contact between the auxiliary roll and the take-up roll is given by

$$(3) \quad a \leq t_2 + t_3$$

in which:

t_3 = radial thickness of auxiliary roll

Of course, the above relations are somewhat lacking in precision because the softness of the rolls, particularly of the fabric on the take-up roll, causes the rolls to press into each other but the relations may be used as an approximate guide in setting the rolls. It is preferable to provide for adjustments of positions of the rolls so that the time when the auxiliary roll first contacts the take-up roll can be regulated.

Typically, for a knitting machine of the above type, each of the rolls 1, 2, 3 and 4 will be of 2-inch diameter. The auxiliary drive roll is positioned about 3 inches out from the upper draw roll and a short distance, say 1 to $1\frac{1}{2}$ inches above it. The auxiliary roll then does not come in contact with the fabric on the take-up roll until the diameter of the take-up roll is about 16 inches and then will remain in contact until the end of a run when the diameter increases to about 32-33 inches.

The mountings for the auxiliary drive roll may be of any simple structure such as brackets 15 fixed to the sides of the carriage as shown in the drawing. These carry bearings in which the shaft of the roll is journaled. The auxiliary roll has a center shaft 16 which is journaled in the bearings. However, the auxiliary roll may be journaled in bearings in support arms pivotally mounted on the sides of the carriage 5 to facilitate adjustment. It is also possible to mount the auxiliary drive rolls for movement in guides toward and away from the take-up roll against fairly strong springs so that the auxiliary drive roll will have better controlled pressure against the take-up roll. It should be noted that the auxiliary drive roll contacts the downwardly moving side of the take-up roll.

The upper draw roll 2 is driven by a crank mechanism. The shaft of the roll 2 carries at its outer end a crank 17. At the top of the carriage 5 there is a horizontal

drive shaft 18 extending from the center of the carriage to the outer edge above crank 17, and journaled in suitable bearings 19 and 20. At the outer end of this drive shaft, there is another crank 21, and a pitman 22 connects cranks 17 and 21. At the inner end of the drive shaft 18, there is a bevelled gear 23. The plate 9 has a depending shank 24. There is a stationary ring gear 25 around the lower end of shank 24 which meshes with bevelled gear 23. Consequently, as the carriage rotates, the drive shaft 18 is turned and the upper draw roll is turned through cranks 17 and 21 and the pitman 22.

A chain drive 26 is provided for the auxiliary drive roll. This includes a sprocket wheel 27 on the shaft of upper draw roll 2, a sprocket wheel 28 on the shaft of the auxiliary drive roll 4 and a chain trained around the sprocket wheels. The sprocket wheel 28 is of somewhat smaller diameter than the sprocket wheel 27 and has fewer teeth. For example, wheel 27 may have 25 teeth and wheel 28 may have 24 teeth. This causes the auxiliary drive roll to turn slightly faster than the upper draw roll 2.

The rolls 2, 3 and 4 are covered with materials to give suitable friction characteristics with the fabric. For example, in the case of fabrics knit from twisted paper yarn, the draw rolls 2 and 3 may have sandpaper covering. The auxiliary drive roll 4 is preferably smoother and might be covered with a finer grade of sandpaper so that it slips slightly against the fabric to compensate for the difference between its speed and that of the upper draw roll. This causes a tightening of the fabric on the roll, in addition to the aid which the auxiliary drive roll gives in turning the heavy roll of fabric.

The invention has now been described by reference to a preferred embodiment which is illustrated in the drawings. However, it will be appreciated that various changes and modifications may be made in the details of construction and the mode of operation without departing from the scope of the invention, as this is set out in the claims.

What is claimed is:

40. 1. A take-up mechanism for circular knitting machines comprising a draw roll, means for turning said draw roll about its axis, a take-up roll for accumulating fabric in a readily compressible roll, means for mounting the ends of said take-up roll with the axis of said take-up roll parallel to the axis of said draw roll, for rotation about its axis, and for movement toward and away from said draw roll, said take-up roll being urged toward said draw roll to peripherally and frictionally engage the draw roll and be turned by it, an auxiliary drive roll, means for mounting said auxiliary drive roll with its axis parallel to that of said draw roll but spaced from a line connecting the axes of said draw roll and said take-up roll, the respective axes of said rolls being positioned at the corners of a triangle, and said auxiliary drive roll being in position to peripherally engage and radially compress the fabric accumulated on said take-up roll only after a predetermined minimum of fabric has accumulated, and means for turning said auxiliary drive roll about its axis, whereby said auxiliary drive roll aids in the turning of said take-up roll by peripherally engaging it only after a part of the fabric has been wound on said take-up roll.

50. 2. A take-up mechanism for circular knitting machines as set forth in claim 1 in which the take-up roll is above the draw roll and is urged toward and against the draw roll by gravity.

55. 3. A take-up mechanism for circular knitting machines as set forth in claim 2 including a second draw roll rotatably mounted below the first draw roll with its axis parallel to the axis of the first draw roll and peripherally engaging said first draw roll.

60. 4. A take-up mechanism for circular knitting machines as set forth in claim 2 in which the auxiliary drive roll is above and to one side of the draw roll.

70. 5. A take-up mechanism for circular knitting machines as set forth in claim 1 in which said means for turning

said auxiliary drive roll is synchronized with said means for turning said draw roll and is constructed and arranged to turn said auxiliary drive roll at a higher peripheral speed than said draw roll.

6. A take-up mechanism for circular knitting machines as set forth in claim 5 in which the surface of said aux-

iliary drive roll is smoother than the surface of said draw roll.
